UNITED STATES PATENT OFFICE.

JOHN JEFFREY PEARSON, OF LONDON, ENGLAND.

DESIGN FOR A BILLIARD-TABLE.

No. 39,173.

Specification for Design.

Patented March 3, 1908.

Application filed November 13, 1907. Serial No. 402,041. Term of patent 14 years.

To all whom it may concern:

Be it known that I, JOHN JEFFREY PEARSON, a subject of the King of Great Britain and Ireland, and resident of 445 Oxford street, London, county of London, England, have invented a new, original, and ornamental Design for a Billiard-Table, of which the following is a specification, reference being had to the accompanying drawings, forming part thereof.

In the drawings: Figure 1 is a perspective view of a billiard table embodying the new design. Fig. 2 is a top plan view thereof.

I claim:

The ornamental design for a billiard table as shown.

JOHN JEFFREY PEARSON.
